UNITED STATES PATENT OFFICE.

CHARLES W. HINMAN, OF BOSTON, MASSACHUSETTS.

GAS-METER.

1,109,225.

Specification of Letters Patent.

Patented Sept. 1, 1914.

Application filed September 20, 1906. Serial No. 335,359.

To all whom it may concern:

Be it known that I, CHARLES W. HINMAN, a citizen of the United States, and resident of Boston, county of Suffolk, Massachusetts, have invented certain new and useful Improvements in Gas-Meters, of which the following is a specification.

In dry gas meters as commonly constructed the ports leading to and from the diaphragm chambers are controlled by two slide valves arranged at an angle of 90 degrees to each other and operated by a crank arm secured to a shaft which is connected with and rotated by the oscillating diaphragm rods. With the valves and ports constructed in the usual manner there is a constant variation in the resistance offered to the flow of gas through the meter with a resultant variation in pressure at the place of use. This variation in the resistance offered to the flow of gas through the meter is due to the variation in the cross sectional area of the open port or ports and of the passage or passages through which the gas flows. When either valve is at the extreme of its throw in either direction the other valve will be in mid position, thus cutting off the flow of gas to or from the corresponding diaphragm chambers. All the gas passing through the meter at this time must therefore flow from the valve chamber through a single port and single passage to a diaphragm chamber and from a diaphragm chamber through a single port and a single passage to the delivery pipe. As the valves move from these positions, gas flows through two ports and passages to two diaphragm chambers and from two diaphragm chambers through two ports and passages to the delivery pipe. The sum of the areas of the openings through the two ports is greater than the area of a single port and this sum increases until the valves are symmetrically positioned with respect to the open ports and then decreases until only a single port is open. The resistance to the flow of gas through the meter is greatest therefore when a valve is at the extreme of its throw and decreases until the valves are symmetrically positioned with relation to the open ports, then gradually increases until the other valve is at the limit of its throw. During the rotation of the crank shaft which operates the valves the resistance will thus fluctuate from the maximum to the minimum four times. This variation in the

resistance offered to the flow of gas through the meter causes an unequal flow of gas and variation of pressure at the place of use which is one of the chief objections to the dry meters as commonly constructed, and this objection increases with an increase in the capacity of the meter. In practising my invention I overcome or minimize this objectionable feature of the dry meters by providing a means for varying the resistance offered to the flow of gas through the meter to compensate for the variation due to the operation of the valve, so that a substantially constant resistance is offered to the flow of the gas through the meter and a substantially uniform and steady flow and pressure insured under all conditions of use. This compensating resistance may be of any suitable form and construction and may be suitably arranged in the passages or openings through which the gas flows. I prefer however, to vary the resistance offered to the flow of gas through the meter by throttling the flow of gas to the valve chamber and to operate the throttling device from the crank shaft from which the valves are operated.

For the purpose of illustration I have shown in the accompanying drawings two forms in which my invention may be embodied.

In these drawings Figure 1 is a sectional plan view showing the valve chamber of a dry meter and so much of the mechanism as is necessary to show the application of the present invention thereto. Fig. 2 is a vertical central section on line 2-2 of Fig. 1. Fig. 3 is a sectional elevation on line 2-2' 3-3 of Fig. 1. Fig. 4 is a detail view of the valve operating crank and of the compensating device; and Figs. 5 and 6 are sectional detail views showing a modified form of compensating device.

In the construction of meter shown in the drawings the shaft 1 which operates the valves is provided at its upper end with a crank 2 which is connected by means of links 3 and 4 with crank arms 5 and 6 secured to the upper ends of the diaphragm rods 7 and 8. The diaphragm rods 7 and 8 are oscillated by the movement of the diaphragms in the usual manner and by their oscillation cause the rotation of the crank shaft 1.

The valves 9 and 10 which control the flow of gas to and from the diaphragm

chambers are connected by links 11, 12 to a crank 13 carried by the shaft 1. The valves are arranged in the usual manner at an angle of 90 degrees to each other and are of the usual D form. These valves in connection with the ports 14, 15 and 16 control the communication between the valve chamber 17 and the diaphragm chambers and between the diaphragm chambers and the 10 delivery passages 171 which lead from the ports 16 to the delivery pipe 18. The inflowing gas flows to the valve chamber 17 through the inlet pipe 19 and an inlet passage 20 which leads from the pipe and discharges through a port or opening 21 into the valve chamber.

The construction of the meter as thus far described is substantially the same as the usual construction and the valves are operated 20 in the usual manner and coöperate with the registering mechanism and diaphragms and diaphragm chambers which are not shown, to measure and register the volume of gas passing through the meter.

25 In the construction shown in Figs. 1-4, the means for compensating for the variation in resistance to the flow of gas through the meter due to the operation of the valves, comprises a series of arms 22 connected to 30 the shaft 1 and arranged to pass over the opening 21 through which the gas flows into the valve chamber. There are four arms 22 symmetrically arranged about the axis of the shaft 1 and these arms are so arranged 35 upon the shaft that one of the arms will be in the position indicated in Figs. 1 and 4 over the opening 21 whenever the valves 9 and 10 are symmetrically positioned with relation to the open ports. When in this 40 position the arm 22 which overlies the opening 21, serves to throttle the flow of gas through the opening 21, thus offering a resistance to the flow of gas through the meter. At this time the valves are in such position 45 that the sum of the open areas of the ports 14 is the greatest and therefore the resistance offered to the flow of gas through the ports and passages leading from the ports to the delivery pipe is the minimum 50 resistance offered by these ports and passages. As the shaft 1 revolves to move the valves, an arm 22 gradually passes from above the opening 21 thus offering a gradually decreasing resistance to the flow of gas 55 through the meter as the resistance offered to the flow by the ports and passages increases. The shaft and proportions of the opening 21 and arms 22 should be such that the gradually varying resistance offered by 60 the arms 22 will compensate for the varying resistance offered by the ports and passages so that a substantially constant resistance will be offered to the flow of the gas through the meter.

65 In Figs. 5 and 6 a somewhat modified

form of compensating device is shown. In the construction shown in these views the inlet passage 20' delivers into the valve chamber through a vertical opening 21' and the compensating device is in the form of 70 a disk secured to the shaft 1 and provided with vertically extending lips or arms 22' arranged to be brought successively in front of the opening 21'. With this construction an arm 22' is gradually brought into position in front of the opening 21' as the valves are moved from a position where one of them is at one end of its throw to a position where the sum of the areas of the open ports is the greatest and is gradually 75 moved away from its position in front of the opening 21' as the valves are moved from this position to the positions where one is at the limit of its throw and the other is in mid position.

80 Other forms and arrangements of compensating devices for varying the resistance offered to the flow of the gas through the meter in inverse relation to the variation in resistance caused by the operation of the valves may be employed without departing 85 from my invention.

Without attempting to point out the various forms and arrangements in which the invention may be embodied, what I claim 95 and desire to secure by Letters Patent is:—

1. A gas meter, having, in combination, valves and valve seats provided with ports offering a variable resistance to the flow of gas according to the position of the valves, means offering an inversely varying resistance to the flow of gas through the meter to compensate for the variation in the resistance offered to said flow by the valves and ports, and means for operating the valves and resistance means, substantially as described.

2. A gas meter, having, in combination, valves and valve seats provided with ports for controlling the flow of gas, a compensating device, and means operating the valves to vary the area of the open ports and operating the compensating device to compensate for the variations in said open port area whereby a substantially constant flow of gas through the meter is maintained, substantially as described.

3. A gas meter, having, in combination, valves and valve seats provided with ports offering a variable resistance to the flow of gas, and a compensating device, and means for operating the valves and for operating the compensating device to maintain a substantially constant flow of gas through the meter, substantially as described.

4. A gas meter, having, in combination, valves and valve seats provided with ports for controlling the flow of gas, to variably throttle the flow of gas through the ports, a throttling device, and means oper-

- ating said valves and also the throttling device to variably throttle the flow of gas inversely to the throttling of the valves, substantially as described.
5. A gas meter, having, in combination, valves and valve seats provided with ports for controlling the flow of gas, means for operating the valves, and a resistance device to compensate for the variable resistance offered to the flow of gas by the valve ports, said resistance device being operatively connected to the valve operating means, substantially as described.
10. A gas meter, having, in combination, valves and valve seats provided with ports for controlling the flow of gas, a crank shaft, means connecting the crank shaft and valves, and a resistance device operated by the crank shaft to compensate for the variable resistance offered to the flow of gas by the valve ports, substantially as described.
15. A gas meter, having, in combination, valves and valve seats provided with ports for controlling the flow of gas, a crank shaft, means connecting the crank shaft and valves, and a resistance device operated by the crank shaft to compensate for the variable resistance offered to the flow of gas by the valve ports, substantially as described.
20. A gas meter, having, in combination, valves and valve seats provided with ports for controlling the flow of gas, a conduit provided with an opening through which the gas flows, and automatic means for operating the valves and for varying the area of the opening inversely to the variation in the area of the open ports, substantially as described.
25. A gas meter, having, in combination, valves and valve seats provided with ports for controlling the flow of gas, a conduit provided with an opening through which the gas flows, a series of arms, and means for operating the valves and for moving said arms successively across the opening to vary its area inversely to the variation in the area of the open ports, substantially as described.
30. A gas meter, having, in combination, valves and valve seats provided with ports for controlling the flow of gas, a conduit provided with an opening through which the gas flows, a series of arms, and means for operating the valves and for moving said arms successively across the opening to vary its area inversely to the variation in the area of the open ports, substantially as described.
35. A gas meter, having, in combination, valves and valve seats provided with ports for controlling the flow of gas, a crank shaft, means connecting the crank shaft and valves, a conduit provided with an opening through which the gas flows, and a series of arms on the shaft arranged to pass across the opening and vary its area inversely to the variation in the area of the open ports, substantially as described.
40. A gas meter, having, in combination, valves and valve seats provided with ports for controlling the flow of gas, a crank shaft, means connecting the crank shaft and valves, a conduit provided with an opening through which the gas flows, and a series of arms on the shaft arranged to pass across the opening and vary its area inversely to the variation in the area of the open ports, substantially as described.
45. A gas meter, having, in combination, diaphragm chambers, valves and valve seats provided with ports for controlling the flow of gas to and from the diaphragm chambers, means for operating the valves, a conduit provided with an opening through which the gas flows, and a series of arms on the shaft arranged to pass across the opening and vary its area inversely to the variation in the area of the open ports, substantially as described.
50. A gas meter, having, in combination, diaphragm chambers, valves and valve seats provided with ports for controlling the flow of gas to and from the diaphragm chambers, means for operating the valves, a conduit provided with an opening through which the gas flows, and a series of arms on the shaft arranged to pass across the opening and vary its area inversely to the variation in the area of the open ports, substantially as described.
55. A gas meter, having, in combination, diaphragm chambers, valves and valve seats provided with ports for controlling the flow of gas to and from the diaphragm chambers, means for operating the valves, a conduit provided with an opening through which the gas flows, and a series of arms on the shaft arranged to pass across the opening and vary its area inversely to the variation in the area of the open ports, substantially as described.

which the gas flows, and means connected with the valve operating means for varying the area of the opening inversely to the variation in the area of the ports caused by the operation of the valves, substantially as described.

11. A gas meter, having, in combination, two valves, means for reversely operating the valves to control inlet and delivery ports, and automatic means for operating the valves and for varying the resistance to the flow of gas through the meter inversely to the variation in the resistance caused by the operation of the valves, substantially as described.

12. A gas meter, having, in combination, a valve chamber, a delivery conduit, valves controlling the flow of gas from the valve chamber into the delivery conduit, means for reversely moving the valves, and means connected with the valve moving means for equalizing the flow of gas through the meter, substantially as described.

13. A gas meter, having, in combination, diaphragm chambers, valves for controlling the flow of gas to and from the diaphragm chambers, mechanism for reversely reciprocating the valves, and means connected with the valve operating mechanism for varying the resistance to the flow of gas through the meter inversely to the variation produced by the reciprocation of the valves, substantially as described.

14. A gas meter, having, in combination, valves and valve seats provided with ports for controlling the flow of gas, valve operating mechanism, and a resistance device for opposing the flow of gas through the meter, said resistance device being operatively connected to the valve operating mechanism, substantially as described.

15. A gas meter, having, in combination, valves, valve seats provided with ports, mechanism for operating the valves, and means operated by the valve operating mechanism to compensate for the variations in the resistance offered to the flow of gas by the varying effective area of the ports, substantially as described.

In witness whereof, I have hereunto set my hand, this 8th day of September 1906.

CHARLES W. HINMAN.

In the presence of—

IRA L. FISH,
KATHARINE A. DUGAN.

Correction in Letters Patent No. 1,109,225.

It is hereby certified that in Letters Patent No. 1,109,225, granted September 1, 1914, upon the application of Charles W. Hinman, of Boston, Massachusetts, for an improvement in "Gas-Meters," an error appears in the printed specification requiring correction as follows: Page 2, line 57, for the word "shaft" read *shape*; and that the said Letters Patent should be read with this correction therein that the same may conform to the record of the case in the Patent Office.

Signed and sealed this 19th day of January, A. D., 1915.

[SEAL.]

R. F. WHITEHEAD,
Acting Commissioner of Patents.
